UNITED STATES PATENT OFFICE.

AUGUST R. SCHOENKY, OF SOMERVILLE, MASSACHUSETTS, ASSIGNOR TO THE REECE SHOE MACHINERY COMPANY, OF BOSTON, MASSACHUSETTS, A CORPORATION OF MAINE.

SEWING-MACHINE.

1,071,355.

Specification of Letters Patent. Patented Aug. 26, 1913.

Application filed February 27, 1912. Serial No. 680,356.

To all whom it may concern:

Be it known that I, AUGUST R. SCHOENKY, a citizen of the United States, residing at Somerville, in the county of Middlesex and State of Massachusetts, have invented certain new and useful Improvements in Sewing-Machines, of which the following is a specification, reference being had therein to the accompanying drawing.

10 My invention relates to sewing machines, and more particularly to that class of machines used in the manufacture of shoes by the welt system, wherein the outsole and welt are sewed together. An example of that class of machine is illustrated in U. S. Patent No. 473,870 of April 26, 1892, and that patent discloses and describes many features and details which may be referred to to supply corresponding features and details 15 not specifically illustrated and set forth in the present application.

An object of the present invention is to generally improve the construction and operation of sole sewing machines of all classes 20 including as an example that of the prior patent above mentioned.

A special object of the present invention is to improve the operation or actuation of the presser foot and to enable it to be opened 30 at any desired point in the progress of the work. Particularly it is proposed to effect this in the present invention by means of a single lever or treadle which when moved by the operator serves the double function 35 of first releasing the devices which hold or clamp the presser foot in position, and second lifting the presser foot.

Other objects will appear during the following description of a particular embodiment of the present invention.

40 To these ends the present invention consists in the novel mechanisms, combinations, arrangements, features and parts as herein-after illustrated and described.

45 I will first describe one form in which my invention may be embodied in a sole sewing machine, and will thereafter point out the novel features in the claims.

In the accompanying drawings forming a 50 part hereof, Figure 1 is a right-hand end view of a machine embodying my invention. Fig. 2 shows somewhat diagrammatically the more important of the elements shown in Fig. 1 involved in the present invention, 55 the same being seen from the same point of

view as Fig. 1 but at a different stage of operation. Fig. 3 is a view similar to Fig. 2 with the parts in a still further stage of operation. Fig. 4 is a view similar to Figs. 2 and 3 with the parts in a still further stage 60 of operation. Fig. 5 is a detail showing in right-hand view the relation of the two pawls with the lever for throwing them out of their engagement with their dogs. Fig. 6 is a right-hand view thereof. Fig. 7 is a 65 partial left-hand elevation of the parts shown in Figs. 1-4 together with additional parts having to do with the measuring of thread. Fig. 8 is a partial front elevation of the parts shown in Fig. 7. 70

Similar letters of reference designate corresponding parts in the several figures of the drawings.

I will first describe some of the parts of the machine already known in the prior patent referred to. It will be noticed that the view of Fig. 1 corresponds generally with the right-hand end view constituting Fig. 3 of the aforementioned prior patent. In fact the general arrangement of said prior patent has been adopted herein as convenient 75 for the purposes of illustration, and the front view shown in the first figure of said prior patent, and the top view shown in the second figure, may be considered as generally representing the location and arrangement of the shaft, cams and other main parts, so that it is believed the present application need not be complicated by including 80 front and top views, especially as the features of improvement herein to be described and claimed, are adequately illustrated in principle and detail in the accompanying figures. In Fig. 1 hereof the lower portions 85 of the frame are cut out for the purposes of condensation and the treadle rod is likewise broken off, it being understood that in the complete machine the work support and adjacent parts will be at a convenient height 90 above the floor or base to best facilitate the 95 operator in the sole sewing operations performed on this machine.

The fixed frame parts A, A may be of any preferred design to properly support the operative parts of the machine. Among 100 the operative parts is the main shaft A shown arranged horizontally, it being supposed to have at the end farthest from the observer in Fig. 1 a driving pulley, and carrying also substantially all of the operating 105

cams of the machine. Among such cams is a cam omitted from the drawings hereof, located at the right-hand end of the driving shaft, and to the left of said cam a second cam C, which is the one seen in Figs. 1, 2, 3 and 4. A fixed part of the machine A² has been heretofore termed a guide-box, it extending horizontally in the lower forward part of the machine and serving to slidably carry a feed slide B². This feed slide in its longitudinal movements carries with it an upright or standard B⁴, at whose upper end is seen a fixed stud a, upon which may be mounted in the usual manner an awl segment. In the upper right-hand part of Fig. 1 is seen a longitudinal shaft or stud F, to which certain other members of the machine are fitted, as will hereinafter appear.

Certain portions of the mechanism of a sole sewing machine to which the present invention *per se* has no relation, are entirely omitted for convenience and clearness of illustration. The work support d hereof may be stationary as shown. The presser foot e² may be of any convenient form such as that indicated, and when the work support is stationary the presser foot will be capable of moving from and toward the work support. Said presser foot is shown as carried on the forward arm of a curved lever e', which is pivoted upon a stud e, said lever e' having a rearward extension as shown. Pivoted also on stud e is an arm e⁴, extending above the rearward portion of lever e'. A sliding link e⁵ affords a connection between the rearward extremities of lever e' and arm e⁴, it being connected to them as follows. Link e⁵ is pivoted upon a stud e³⁰ on lever e', and it extends therefrom through an aperture in a lug e⁵ formed upon arm e⁴. Beyond the lug e⁵ is a sleeve or elongated washer e⁶, and beyond that is a helical spring e⁷ confined between the washer e⁶ and a regulating nut e⁸, by which the compression of the spring e⁷ is regulated. The link e⁵ will pass sufficiently loosely through the aperture in lug e⁵ to permit a moderate, relative movement as between lever e' and arm e⁴, the spring e⁷ tending to hold the lever and arm toward each other. The purpose of the arm e⁵ and the rearward part of lever e' is to afford a plurality of coöperating movable members for carrying corresponding ratchet toothed racks or dogs e⁹, e¹⁶, the latter in turn for coöperating with pawls e¹⁰ and e¹⁷ respectively in the actuation of the presser foot. The pawls e¹⁰ and e¹⁷ may in fact consist of two or more pawls of varying lengths for the purpose of finer adjustment, and for the same purpose the dogs e⁹, e¹⁶ may if desired have finer teeth than as shown. The pawl e¹⁰ is shown pivoted upon a swinging lever e¹², which is fulcrumed upon a fixed stud e¹³, said lever having a roller at e¹⁴ for engaging groove e¹⁵ in

cam C. In this way the cam is able to effect the swinging of the lever and the up and down movements of the pawl and dog e⁹. The pawl e¹⁷ engages the dog e¹⁶ on the lever e', and said pawl is loosely mounted on a stud e¹⁸ rendered fixed by attachment to a portion of the frame of the machine. Pawl e¹⁷ has a rearward extension e¹⁹ normally acted upon by a spring e²⁰, which keeps said pawl e¹⁷ in engagement with dog e¹⁶. The pawl e¹⁰ is likewise acted upon by a suitable spring e²¹ carried by the lever e¹², thus keeping it normally in engagement with dog e⁹.

At this point we will suspend the description of the pawls and dogs and their manner of operating the presser foot, and will proceed to describe certain other parts of the mechanism.

Parts of the thread measure regulating means are indicated and will now be referred to. Depending from the rearward end of lever e' is an upwardly and downwardly moving member which may be termed a frame f, whose position at all times obviously depends upon the position of the presser foot. The lower end of the frame is slotted and it straddles the rock shaft f' which guides it. A member f⁴ which may be termed a slide box is adapted to oscillate slightly, it having its lower end pivotally connected at f³, directly or indirectly, to the frame f. The upper end of the slide box f⁴ is pivotally connected to a substantially horizontal connecting rod f¹³, which when actuated causes the oscillation of the slide box. The rear side of the slide box f⁴ is vertically slotted to receive a slide block f⁵, surrounding a stud f¹⁰ provided at the upper end of a short oscillating arm f¹² secured upon the aforementioned transverse rock shaft f'. These parts *per se* form no part of the present invention. The rock shaft f' controls the thread measuring as follows: At its left end as seen in Fig. 8 it carries a forwardly extending arm g having a thread roller g⁴ or pulley at its outer end. The thread t from the wax pot and tension passes forwardly making a turn and a quarter around the thread wheel t', whence the thread passes to the pulley g⁴ and around it, thence to and around a thread lock wheel g', thence to and around the auxiliary take-up g⁶ and thence to and around the main take-up g⁹ whence the thread passes to the loopers and needles. The lock wheel g' is adapted to be contacted by a shoe g⁷ at intervals to lock the thread. While the thread is locked the take-up g⁹ operates to take up the thread from the previous stitch and at the same time the measuring wheel g⁴ rises and descends to draw from the supply and thence measure off the proper quantity of thread for the succeeding stitch. The control of the amount of thread measured will now be understood. The thicker

the work beneath the presser foot, the lower will be the normal position of the frame f . Therefore a given oscillation of the slide box f^4 will effect a greater oscillation of the thread measuring levers than would be the case with a piece of thin work beneath the presser foot.

The manner of actuating the connecting rod f^{13} may be as follows. It is shown pivotally connected at f^{14} to the downward arm of a bell crank lever f^{15} mounted on the fixed stud F before mentioned, while the horizontal or forward arm of bell crank lever f^{15} has at its forward end a roller f^{16} projecting into a groove (not shown) of one of the cams on shaft A' , such groove being so shaped as to effect the oscillation referred to at the proper point in the formation of each stitch.

I will now refer to the normal operation of the presser foot. A tendency to hold the presser foot down upon the work is created by a suitable spring n^8 secured at a convenient point in the frame and pressing upwardly yieldingly against the lower end of the frame f already mentioned. The work Z , such as the sole of a shoe, is shown as lying between the work support d and presser foot e^2 , the latter being held down yieldingly as just explained. The pawls and dogs are now to come into play to forcibly clamp the work during the operation of the awl and the needle. This clamping is initiated by the eccentric portions of cam grooves e^{15} acting upon the roller e^{14} of lever e^{12} . The lever on being lifted after having been lowered causes the pawl e^{10} to engage dog e^9 , the pawl e^{17} being at the same time permitted to engage dog e^{16} . On swinging upwardly the lever e^{12} acting through pawl e^{10} and dog e^9 , effects the lifting of the arm e^4 carrying dog e^9 . This in turn imposes compression upon the strong spring e^7 , which acting through rod e^8 pulls up upon the rear end of lever e^1 , thereby forcibly pressing down the presser foot e^2 with a pressure which may be regulated by increasing or decreasing it according to the character of the stock, by the adjustment of the nut e^8 . As this takes place, the pawl e^{17} whether it is single or multiple, engages itself in the dog e^{16} so as to lock and hold firmly down the presser foot against the stock. While in this position the awl will rise to perforate the stock, and thereafter the feed slide B^3 and upright B^4 carrying the awl will shift for feeding the stock. This feeding obviously could not take place with the stock under heavy clamping pressure, and therefore before the awl commences the feeding movement, the pressure of the presser foot must be released. This is effected by the depression of the lever e^{12} by the cam groove e^{15} , this effecting first the disengagement of the pawl e^{10} from its dog,

and then the disengagement of the pawl e^{17} from its dog. The former disengagement is caused by the pawl e^{10} striking against a fixed pin or stud 89 , which lifts the pawl against the resistance of its spring. The latter operation is effected by the heel 189 of lever e^{12} striking the heel e^{19} of pawl e^{17} . Thus the presser foot is bearing upon the stock only with the slight force due to spring n^8 at the time the feeding takes place.

All of the parts hereinabove described while not identical, correspond to some extent with parts shown in Patent No. 473,870, and as a matter of convenience all of the reference characters above employed are taken as far as possible from said prior patent. In said prior patent when for some reason the operator desired to remove or readjust the work before completion, he would lift the presser foot by means of the hand lever e^8 , but before he could do that, it would first be necessary for him to disconnect both pawls and dogs. If therefore it was possible at all for the operator to lift the pawls by hand, it thus was necessary for the operator to perform at least two independent hand operations for releasing the work, whereas the work itself is required to be held firmly by the operator. In the mechanism hereinafter to be described, the operator is permitted to release the work without removing either hand therefrom, and as will be seen this is permitted by my invention to be effected by a single action, that is the movement of a single lever such as a foot treadle, which performs the two operations of first releasing the pawls and dogs, and second lifting the presser foot. The details of this and of the subsidiary parts of my present improvement will now be described.

One element of my improvement consists of a member R in the form of a lever constructed and arranged to release both pawls e^{10} and e^{17} . This pawl releasing member is indicated in all the figures hereof, but is best shown in Figs. 5 and 6. It may be pivotally mounted on the same stud e^{18} that carries the pawl e^{17} , and it may comprise besides its main or horizontal portion R an upward extension r so shaped as to contact with pins r' and r^2 mounted respectively on the sides of the pawls e^{17} , e^{10} , whereby the lever R on being swung will move both pins and thereby lift both pawls from their respective dogs. The extension r may be recessed or shaped at r^3 for the purpose of clearing the fixed stud 89 already referred to, and the recess may be so shaped that the stud 89 will form a convenient stop to prevent excessive movement of the lever R . The pawl releasing lever is to have convenient connections so that it can be actuated at will, as will be herein-after described, and to permit this it is pro-

vided at r^4 with a lateral projection or extension.

My improvement also contemplates a movable or depressible part which when depressed will cause the elevation of the presser foot. Of course any part such as a lever could be employed as a presser foot lifter. For the purposes, however, of my invention, the part that is to serve this purpose should have a suitable location in the machine and at the same time should not be in the way so as to interfere with other mechanism. To carry out the ends hereof, I have conceived the idea of employing as a presser foot lifter, a certain member that is already in use in the machine for another purpose, namely one of the members that takes part in actuating the thread measure. This member is the aforementioned rod f^{13} which is longitudinally oscillated by the lever f^{15} at the rear end so that at the front end it will effect the oscillation of the slide block f^4 for actuating the thread measuring device. It will be observed that although the rod f^{13} is intended to be longitudinally oscillated, it is so connected to the lever e' through the frame f that the depression of the rod f^{13} causes the depression of the lever and the elevation of the presser foot. As an incidental to rendering the rod f^{13} more adaptable to the functions it is to perform under my invention, I have recessed its upper side to form a bearing surface s , by which the rod may be depressed, and this surface will be of such length as to freely permit the oscillations of the rod notwithstanding the entry into the recess of the part which is to depress it.

Another feature contemplated in my invention is enabling the lifting of the presser foot without requiring the operator to remove either hand from the work for that purpose. To this end a lever is employed operable by the knee or foot, for example the treadle T hinged at its rear at t and acted upon by a spring t' which tends to hold it elevated while permitting its depression by the foot of the operator. A treadle rod t^2 extends from an intermediate point of the treadle upwardly to where at its upper end it is pivotally connected to the forward end of an arm t^3 which extends forwardly to where it is secured upon a shaft t^4 fitted in suitable stationary bearings so as to be capable of a slight rotation. The arm t^3 will be conveniently located with respect to the length of the shaft t^4 , so as to permit the treadle to be conveniently located for the foot and directly beneath the arm t^3 . At another point upon the shaft t^4 to the right of arm t^3 that is between that arm and the observer in Figs. 1, 2, 3, 4, is a second arm t^5 extending forwardly and having at its forward end a contact, such for example as the adjustable contact screw t^6 . The contact t^6

is intended to act upon so as to depress the presser foot lifter f^{13} , and to this end the contact will either be located directly over the lifter or over an intermediate element as r^4 which in turn is located over the lifter. By the described arrangement it will be seen that on depressing the treadle the shaft t^4 is swung and the contact t^6 causes the rod f^{13} to move downwardly, thereby lifting the presser foot.

My present invention also contemplates that a single lever shall effect both operations, namely the disengagement of the pawls and dogs on the one hand, and the lifting of the presser foot on the other hand. This is permitted in the described construction since the lever or treadle T is connected not only to actuate the presser foot lever f^{13} , but is also connected so as to throw the pawl releasing member R . Thus it has already been described that the member R has a lateral projection r^4 , and this projection will be seen to extend directly beneath the contact t^6 . It in fact for convenience is the intermediate element between the contact t^6 and the presser foot lifter f^{13} . The arrangement is therefore such that the depression of the lever T effects both the functions recited.

My invention also contemplates a certain order of operation of the described parts, namely, that the pawls shall be released before the presser foot lifter is actuated. This result is secured by the fact that as seen in Fig. 2 the pawl releasing member's extension r^4 is spaced slightly above the presser foot lifting rod f^{13} , the consequence of which is that in depressing the foot treadle, contact t^6 causes first the release of the pawls followed in the same operation and practically instantaneously, by the depression of the rod f^{13} and thereby the lifting of the presser foot.

By the above described mechanism, all of the objects hereinbefore recited are attained, and other objects, which will be apparent to those skilled in the art.

The operation of the mechanism as a whole will be sufficiently understood from the above description, but the following further statement will be of assistance in giving a full understanding of the improvement. Fig. 1 shows the work Z under the heavy compression of the presser foot e^2 that prevails during the operations of the awl and needle, the lever e^{12} being here held upwardly by the cam groove e^{16} acting on roller e^{14} . In this figure both of the pawls e^{10}, e^{17} are seen to be in engagement with both of the dogs e^9, e^{16} , the presser foot being thereby locked in clamping position. The foot treadle is in upward position and is inactive. Fig. 2 shows a different stage of operation. During each feeding movement as the line of stitches is formed the

110

115

120

125

130

work must be sufficiently unclamped to permit relative feeding movement, and this must occur at regular intervals. The cam groove e^{15} effects this by causing the depression of the lever e^{12} , which as previously explained, automatically effects the disengagement of both the pawls from their respective dogs. The figure shows the pawls disengaged. The figure also shows a slight space between the work and the presser foot, merely as conveniently indicating that the heavy clamping pressure is not in force. The presser foot, however, is held down lightly by the force of spring n^6 . If now the operator desires to raise the presser foot whether at the end of the operation or at any other point of time, he may do so by the use of my invention irrespective of the normal operation of the presser foot and the pawls and dogs which operate it. Thus now with the parts in the position of Fig. 1, if the treadle T be depressed, the first thing that will occur will be the release of the pawls, and this stage of the operation is shown in Fig. 3. The treadle rod t^2 has been pulled downwardly to cause the arm t^5 to swing downwardly, the contact t^6 thereby forcing downwardly the extension r^4 of the pawl releasing member R , thus releasing the pawls as shown. By comparison with Fig. 2, the contact t^6 and the extension r^4 will be seen to have been depressed, but the rod f^{13} is not depressed. The descent of the treadle T being continued, the contact t^6 and extension r^4 having come into contact with the upper surface s of the presser foot lifter f^{13} , the latter begins to move downwardly and the three parts continue their downward movement together to the position shown in Fig. 4. This causes a decided lowering of the left end of the presser foot lifter f^{13} , its right end being supported against possibility of depression. Its left end being connected as aforesaid with the frame f , moves that frame downwardly, and with it is carried downwardly the right-hand end of lever e' , whose left-hand end is therefore lifted, carrying with it the presser foot e^2 , which as seen in Fig. 4 is considerably above the work Z .

I have thus in the above described mechanism very conveniently and effectively carried out the purposes hereof. It is obvious that the details of the elements, their form and arrangement, may be variously modified, and I therefore do not intend to impose any restrictions on my broad invention except as set forth in the appended claims.

This improvement involves the novel combination of a presser foot, e^2 , movable toward and from the work, and means (comprising the cam arm e^{12} and the pawls, etc.), for intermittently clamping the presser foot upon the work, and a device (the lever R) for releasing or tripping the clamping

means, and a part, whether the treadle, or rod t^2 , or arm t^5 , or extension r^4 , which is shiftable or depressible at will and is arranged to first operate the releasing device and to then lift the presser foot, in one operative movement. It will be noticed that when the treadle is depressed it does not lower the arm e^{12} , and the pawls are merely tripped to unlock the presser foot without first reducing and releasing the heavy pres- 70

75

What I claim and desire to secure by Letters Patent is:

1. In combination, a presser foot movable toward and from the work, a movable arm 80 having means for automatically operating it during a portion of each stitch to clamp the presser foot forcibly upon the work, a releasing device independent of said arm but adapted when actuated to release the presser 85 foot from the clamping action of said arm, and a part or lever shiftable at the will of the operator adapted when shifted to first actuate the said releasing device and then lift the said presser foot. 90

2. In combination, a presser foot movable toward and from the work, a movable arm having means for automatically operating it during a portion of each stitch to clamp the presser foot forcibly upon the work, a releasing device independent of said arm but adapted when actuated to release the presser 95 foot from the clamping action of said arm, a movable presser foot lifter or arm having a movable connection with the said presser foot, and a part or lever shiftable at the will of the operator adapted when shifted to first actuate the said releasing device and then actuate the said lifter. 100

3. In combination, a presser foot movable 105 toward and from the work, means for intermittently clamping the presser foot forcibly upon the work, a device for releasing said clamping means, a presser foot lifter, and a part shiftable at will constructed and arranged to first operatively move said device, and on continued movement to cause said device to move said lifter. 110

4. In combination, a presser foot movable toward and from the work, a member connected to and movable in unison with said presser foot adapted to control a thread measuring device, means for intermittently clamping the presser foot upon the work and a part or lever operable at will for first effecting the release of said clamping means, and then shifting said member to lift the presser foot. 115

5. In combination, a presser foot movable toward and from the work, a member connected to and movable in unison with said presser foot adapted to control a thread measuring device, means for intermittently clamping the presser foot upon the work, a device for releasing said clamping means, 125

and a part or lever operable at will for first operating said releasing device, and then shifting said member to lift the presser foot.

6. In combination, a presser foot movable 5 toward and from the work, devices and power connections for intermittently clamping the presser foot upon the work, a releasing device independent of said connections adapted when shifted to release said clamping devices, a lifter adapted when shifted to lift the presser foot, and a part shiftable at will constructed and arranged to shift said releasing device and lifter so as to first release said clamping devices and then lift the 10 presser foot.

7. In combination, a presser foot movable toward and from the work, devices and power connections for intermittently clamping the presser foot upon the work, a releasing device independent of said connections adapted when depressed to release said clamping devices, a lifter adapted when depressed to lift the presser foot, and a part 20 depressible at will constructed and arranged to depress said releasing device and lifter, the lifter being spaced below the releasing device whereby the clamping devices are first released and the presser foot then lifted.

8. In combination, a presser foot movable 30 toward and from the work, devices and power connections for intermittently clamping the presser foot upon the work, a releasing device independent of said connections adapted when depressed to release said 35 clamping devices, a lifter adapted when depressed to lift the presser foot, and a part depressible at will constructed and arranged to depress said releasing device and the lifter arranged to depress the lifter in such 40 wise that the clamping devices are first released and the presser foot then lifted.

9. The combination with a presser foot, movable downwardly upon the work and upwardly, a part or frame movable up- 45 wardly and downwardly in unison there-

with, thread measuring mechanism controlled by said frame, presser foot clamping means, a clamp releasing device, and a single lever having connections for first operating said releasing device and then lifting the 50 presser foot through said part or frame.

10. The combination with a presser foot, movable downwardly upon the work and upwardly, a part or frame movable upwardly and downwardly in unison there- 55 with, thread measuring mechanism controlled by said frame, an oscillating rod constituting part of said measuring mechanism, presser foot clamping means, a clamp releasing device, and a single lever having 60 connections for first operating said releasing device and then lifting the presser foot through the said oscillating rod.

11. The combination with a movable presser foot, of a clamping device therefor, 65 a depressible rod having connections for elevating the presser foot, a depressible clamp releasing lever located over said rod, and means for depressing said lever and thereby said rod, at will, said lever normally spaced 70 above said rod, whereby the clamping device is released before the presser foot is lifted.

12. The combination with a movable presser foot, of a clamping device therefor, 75 a depressible rod having connections for elevating the presser foot, a depressible clamp releasing lever located over said rod, and a foot treadle having connection with, for depressing said lever and thereby said rod, 80 at will, said lever normally spaced above said rod, whereby the clamping device is released before the presser foot is lifted.

In testimony whereof I affix my signature in presence of two witnesses.

AUGUST R. SCHOENKY.
